UNITED STATES PATENT OFFICE

100,764

DESIGN FOR A TEXTILE FABRIC

Curt Erwin Forstmann, Montclair, N. J.

Application October 5, 1935, Serial No. 58,856

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing forming part thereof.

In the drawing, the sole figure of which is a plan view of a piece of the textile fabric embodying the design of the present invention, the cloth depicted is of a single color.

The design comprises spaced elevated stripes of

substantially uniform width arranged parallel in warpwise and weftwise series, defining depressed squares therebetween, the weftwise stripes being composed of relatively small stitches, while the warpwise stripes are composed, between the weftwise stripes, of groups of stitches, being larger than the stitches comprising the weftwise stitches giving the weftwise stripes the appearance of crossing over the warpwise stripes.

I claim:

The ornamental design for a textile fabric as shown and described.

CURT ERWIN FORSTMANN.
